UNITED STATES PATENT OFFICE.

BENJAMIN F. KURTZ, OF AVALON, PENNSYLVANIA, ASSIGNOR TO PRESSED STEEL CAR COMPANY, OF PITTSBURGH, PENNSYLVANIA, A CORPORATION OF NEW JERSEY.

BRAKE-ADJUSTING MECHANISM.

Application filed November 7, 1921. Serial No. 513,251.

To all whom it may concern:

Be it known that I, BENJAMIN F. KURTZ, a citizen of the United States, residing in Avalon, in the county of Allegheny and State of Pennsylvania, have invented certain new and useful Improvements in Brake-Adjusting Mechanism, of which the following is a specification.

This invention relates to railway car 10 brakes and has for an object the provision of means whereby the spring, which prevents the brake shoe from dragging on the wheel when the brake is released, may be adjusted so that the brake shoe will be maintained in its proper position when the brake 15 is released without permanently bending the spring to obtain such adjustment.

Referring to the drawing in which like reference characters refer to like parts, Fig. 20 1, is a side elevational view of a portion of a railway car truck and brake mechanism having the invention embodied therein. Fig. 2, is an end elevational view of the same taken in the direction as indicated by the 25 arrow A in Fig. 1.

Referring now in detail to the drawing the reference character 1 indicates a truck frame which may be of any suitable form or construction and having wheels 2 mounted 30 therein in any preferred manner.

The reference character 3 indicates a dead lever of the brake mechanism, the upper end portion of which is pivotally connected with the truck frame through the medium of a pin 4. The lower end portion of this lever is provided with a brake shoe head 5 such head being pivoted to the lever through the medium of a pin 6. The back portion of the head comprises spaced portions 7 between 35 which the lower portion of the lever 3 extends and to which the lever is pivotally connected. Below the lower end of the lever 3 the head 5 is provided with webs 8 and 40 9 which extend between the spaced portions 7 and are preferably integral therewith. These webs are spaced apart providing an opening 10 between them. The web 8 adjacent the opening 10 is provided with an outwardly projecting lug 11 which is preferably integral with the web. For the purpose of holding the head 5 in its proper position so that the shoe 12 secured thereto will not drag on the wheel when the brake is released, a spring 13 is provided, the upper end 45 portion 14 of which slidably engages the

lever and the lower end portion 15 contacts with and passes over the lug 11 and through the opening 10 and engages the underside of the web 9. Adjacent the lug 11 the web 8 is provided with an opening 60 through which a bolt 16 passes, the head 17 being adapted to engage the web 8 and the threaded portion 18 extending through the opening and through an opening in the spring 13. The end portion of the bolt 65 which extends through the spring is provided with a nut 19 which is adapted to engage the spring between the lever and the lug 11. When the spring 13 is applied to the head 5 and it is desired to adjust the 70 spring so that the shoe will be held in its proper position, the nut is turned in the direction as indicated by the arrow in Fig. 2 which forces the end portion 14 of the spring into close contact with the lever 3, 75 the lug 11 providing sufficient clearance between the spring and the head for proper adjustment. It will be noted that by the use of the nut 19 the tension on the spring may be increased or decreased as desired 80 without permanently bending the spring as has heretofore been the practice.

Having thus described the invention what I claim as new and desire to secure by Letters Patent is:—

85

1. In a brake mechanism, a brake lever, a brake shoe head pivotally connected with said lever and a spring mounted on said head and engaging said lever and means intermediate the ends of said spring for adjusting the tension of said spring.

2. In a brake mechanism, a brake lever, a brake shoe head, pivotally connected with said lever, a spring mounted on said head and engaging said lever and screw means 95 intermediate the ends of said spring for adjusting the tension of said spring.

3. In a brake mechanism, a brake lever, a brake shoe head pivotally connected with said lever, a spring mounted in said head, a 100 projection adapted to space a portion of said spring away from said head and means adjacent said projection for adjusting the tension of said spring.

4. In a brake mechanism, a brake lever, a 105 brake shoe head pivotally connected with said lever, said head having spaced back portions, webs extending between said spaced portions, a lug projecting from one of said webs, a spring engaging said lever 110

and lug and passing between said webs and means for adjusting the tension on said spring.

5. In a brake mechanism, a brake lever, a brake shoe head connected with said lever, said head having spaced back portions, spaced webs extending between said back portions, a spring engaging said lever and webs, and means independent of said lever for adjusting the tension on said spring.

10. 6. In a brake mechanism, a brake lever, a brake shoe head, a spring connected with

said head adapted to engage with said lever, a lug on said head adapted to engage with said spring and means intermediate the ends 15 of said spring and between said lever and lug for adjusting the tension on said spring.

In testimony whereof I affix my signature in the presence of two witnesses.

BENJAMIN F. KURTZ.
